CLAIM

The ornamental design for a combined jeans fly and waist band portions, and jewelry therefor, as shown and described.

DESCRIPTION

FIG. 1 is a perspective view of a combined jeans fly and waist band portions and jewelry therefor showing my new design;

FIG. 2 is an enlarged partial sectional view along the line 2—2 of FIG. 1; and,

FIG. 3 is an enlarged partial sectional view along the line 3—3 of FIG. 1.

The broken line showing of jeans in FIG. 1, is for illustrative purposes only and forms no part of the claimed design. The rear of the combined jeans fly and waist band portions and jewelry therefor forms no part of the claimed design.
